UNITED STATES PATENT OFFICE.

CHARLES BUTCHER, OF CAMBRIDGE, MASSACHUSETTS.

POLE OR SHAFT SUPPORTER.

SPECIFICATION forming part of Letters Patent No. 634,801, dated October 10, 1899.

Application filed March 30, 1899. Serial No. 711,096. (No model.)

To all whom it may concern:

Be it known that I, CHARLES BUTCHER, a citizen of the United States, residing at Cambridge, in the county of Middlesex and State 5 of Massachusetts, have invented new and useful Improvements in Pole or Shaft Supporters, of which the following is a specification.

This invention relates to improvements in pole or shaft supporters for the purpose of holding a carriage pole or shafts in a more or less elevated position when placed in the wagon shed or barn, and it is carried out as follows, reference being had to the accompanying drawings, wherein—

15 Figure 1 represents a front view of a carriage, showing a portion of the pole or shaft supporter in section. Fig. 2 represents a sectional side elevation of a carriage, showing the pole or shaft supporter longitudinally in section. Fig. 3 represents a detail perspective view of the improved pole or shaft supporter, and Fig. 4 represents a cross-section on the line 4 4 shown in Fig. 3.

Similar letters refer to similar parts wherever they occur on the different parts of the drawings.

In the drawings, Figs. 1 and 2, A represents a carriage-body of any suitable size or shape, having secured to its forward end the usual 30 springs B B', the latter being pivoted by means of the king-bolt C to the forward axle D, on which d d are the wheels, as usual.

E represents the shafts or thills, as usual, pivoted to the front axle D and provided with 35 a cross-bar e, as is common in devices of this kind.

My improved pole or shaft supporter consists of a bar or lever F, the forward end of which is slotted or forked, as shown at f in 40 Figs. 2 and 3. In the slotted or forked portion f is received the adjustable supporting-link G, which is forked or slotted, as shown at g in said Figs. 2 and 3, for the purpose of receiving a clamping-bolt h passing through 45 a perforation in the bar or lever F and the forked or slotted portion of the link G. H is a thumb-nut on the screw-bolt h for securing the link G in any desired position to the bar or lever F, as shown in Fig. 3. On the 50 under side of the bar F, I make a longitudinal groove F' (shown in Figs. 1, 2, and 4) for the purpose of receiving the head of the king-bolt C when the pole or shaft supporter is in use, as represented in Fig. 2. By having 55 such groove F' on the under side of the lever

F the latter may be placed directly below the center of the carriage-body, so as to receive the head of the bolt C, thus preventing the lever F from moving sidewise or slipping downward when placed in the position shown 60 in Figs. 1 and 2.

In using the improved pole or shaft supporter the lever F is placed in the position shown in Figs. 1 and 2, the rear end of said lever resting against the under side of the 65 carriage-body A and its middle or forward end resting on the lower spring B' in such a manner that the head of the king-bolt C is received in the groove F' on the under side of the lever or bar F, as fully represented in 70 Figs. 1 and 2. The pole or shafts E are then raised more or less, as may be desired, and the link G placed below the cross-bar e on the pole or shafts and secured to the bar or lever F by means of the fastening-bolt h and 75 nut H, as shown in Fig. 2.

The device is very simple in construction, is composed of very few parts, and is readily adjustable for carriages or wagons of any kind. When not needed for use, the device 80 may be folded together in a very small compass.

What I wish to secure by Letters Patent and claim is—

The herein-described pole or shaft sup- 85 porter comprising a bar F consisting of a single integral piece of wood provided on its under side with a longitudinal groove F' and bifurcated at one end, as at f, a shaft-sup- 90 porting link G longitudinally slotted or forked 95 from one end to near its opposite end and disposed between the forked ends of the said bar, an adjusting-bolt h extending through perforations in the forked ends of the bar and through the slot in the link, and a thumb- 95 nut for tightening said bolt to secure the parts in their adjusted positions, the grooved under side of the bar being arranged to engage the king-bolt of the vehicle and the upper end of the link operating to engage and 100 support the pole or shafts, substantially as described.

In testimony whereof I have hereunto set my hand in presence of two subscribing witnesses.

CHARLES BUTCHER.
